UNITED STATES PATENT OFFICE.

FRANKLIN C. HOCKENSMITH, OF IRWIN, PENNSYLVANIA.

CAR-AXLE LUBRICATOR.

SPECIFICATION forming part of Letters Patent No. 394,362, dated December 11, 1888.

Application filed September 10, 1888. Serial No. 285,011. (No model.)

To all whom it may concern:

Be it known that I, FRANKLIN C. HOCKENSMITH, of Irwin, in the county of Westmoreland and State of Pennsylvania, have invented 5 certain new and useful Improvements in Axle-Lubricators for Railroad-Cars; and I do hereby declare the following to be a full, clear, and exact description of the invention, such as will enable others skilled in the art to which 10 it pertains to make and use it, reference being had to the accompanying drawing, which forms part of this specification.

My invention relates to an improvement in axle-lubricators for railroad-cars; and it consists in the combination, with a wheel, of two oil-chambers placed upon opposite sides thereof, each chamber being provided with an internal flange or bracket, as will be more fully described hereinafter.

20 The object of my invention is to place inside of each of the chambers a flange, bracket, or partition which extends past the filling-hole for the purpose of enabling a larger quantity of oil to be placed in each chamber without 25 running out, and to prevent the oil from spilling through the filling-hole, especially when the wheel is running upon a curve.

The accompanying drawing represents a vertical section of a wheel to which my invention is applied.

30 A represents the wheel, and B its hub, which is provided with a lubricating-groove, C, which makes connection with each one of the lubricating-chambers D, as shown. I do not limit 35 myself to the particular form of groove shown, for this may be varied at will; but the groove should make connection with each of the chambers, so that any oil which runs from one chamber, owing to the position in which 40 the wheel is, will pass into the other one, and thus prevent it from leaking through the hub.

The oil-chambers D may be made of any desired shape, and each one is provided with a filling-hole, G, upon its outer side, through 45 which the lubricating material is poured. Inside of each chamber is a flange, partition, or bracket, I, which extends from the outer side of the chamber a suitable distance past the filling-opening, but which does not extend all 50 the way to the hub, as shown.

The lubricator on being poured through the filling-hole first passes through the outer and smaller chamber, O, from which it can freely pass as the wheel revolves into the larger chamber. As the wheel revolves, the oil 55 evenly fills both compartments of the chambers D, and these partitions serve to prevent the oil from being thrown by centrifugal force through the filling-openings while the wheels are running upon a curve, and also to enable 60 a larger quantity of oil to be poured into the chambers D than can be done where no partitions are used. The partitions I prevent the oil from having an endwise movement, which would cause the oil to be thrown out of the 65 openings G. If the partitions are not used, there is nothing to prevent the oil from being dashed directly through the opening G, and therefore the partitions, by preventing this waste of the oil, enables a larger quantity to 70 be poured into the chambers than can be done without them. These partitions serve as guards for the filling-holes and prevent any waste of oil therefrom. Where no brackets are used, but comparatively a small amount 75 of oil can be poured into the chambers before it will begin to waste through the filling-holes, and thus the wheels require to be lubricated frequently. Brackets, flanges, or partitions prevent the oil from running out, because the 80 brackets extend beyond the filling-openings, and a greater quantity is held in the large compartments of the lubricating-chambers D.

Having thus described my invention, I claim—

85 The combination of the wheel with the oil-chambers applied thereto, the groove in the hub, and the flanges, brackets, or partitions placed in the chambers and extending at their inner ends past the filling-holes, substantially 90 as shown and described.

In testimony whereof I affix my signature in presence of two witnesses.

FRANKLIN C. HOCKENSMITH.
